UNITED STATES PATENT OFFICE.

JOHN J. BOERICKE, OF MERION, PENNSYLVANIA.

CRUCIBLE.

1,277,032.

Specification of Letters Patent. Patented Aug. 27, 1918.

Application filed July 20, 1914, Serial No. 851,883. Renewed June 23, 1918. Serial No. 242,662.

To all whom it may concern:

Be it known that I, JOHN J. BOERICKE, a citizen of the United States, residing at Merion, in the county of Montgomery and State of Pennsylvania, have invented certain new and useful Improvements in Crucibles, of which the following is a specification.

This invention relates to refractory crucibles for use in carrying out metal reduction and related metal founding processes, and it has for its primary objects the provision of an improved separable crucible of simple and economical construction, the parts of which may be readily assembled and separated to remove the contents.

In conjunction with the foregoing, my invention also contemplates the provision of a refractory lining which will withstand high temperatures without disintegration, but which will readily break down when the parts of the crucible are separated.

The foregoing, together with such other objects as may hereinafter appear or are incident to my invention, I attain by means of a construction which I have shown in preferred form in the accompanying drawings, wherein—

Figure 1 is a plan view of a crucible embodying my invention in position on a portable truck; Fig. 2 is a side elevation of the device of Fig. 1; and Fig. 3 is a section through the crucible on the line III—III of Fig. 1.

Referring now to the drawings, it will be seen that my improved crucible comprises a bottom member or slab A preferably composed of fire-brick, and a plurality of ring-like members B superimposed on one another. The members B may be of any desired shape, but I prefer them in the shape of rings as this construction is simple, economical, and easy to assemble. Each ring is comprised of a plurality of bricks 7 set on end and any form of a refractory brick may be used. The bricks are clamped together by a clamping ring or collar 8, the free ends 9 of which are drawn together by means of nuts and bolts 10 and 11, as shown. The collars 8 are preferably made of metal. In practice I prefer to use three of the ring-

like members B merely placed one on top of the other; but it is obvious that any number of rings may be employed, depending upon the character of the work to be done. 55 The bottom member A rests upon a metal plate 12 carried on the truck C.

After the parts of the crucible have been assembled, it is desirable to provide a refractory lining 13 not only to prevent waste, 60 but also to prevent the metal from adhering to the bricks, which would prevent the separation of the rings B. To accomplish this, the refractory lining should be capable of withstanding high temperatures without 65 disintegrating, and must at the same time be capable of being easily broken down when the rings are successively lifted off. In other words, the lining is a temporary, 70 destructible one, sufficiently cohesive and refractory to withstand, for example, a metal reduction operation or some similar metallurgical or metal founding operation. I prefer to use a refractory lining made in accordance with the methods described in 75 my co-pending application, Serial No. 851,887, filed July 20, 1914.

The advantages of my invention may be best shown by a specific example of its use. In reducing the rarer metals from 80 compounds by the alumino-thermic method, the compounds and aluminum in some form are mixed, placed in a crucible, and the reaction induced by igniting a portion of the mass, from which it spreads to the entire mass. 85 After the reduction is completed and the metal and slag have solidified, the rings B (because of the destructible lining), may be lifted off, one after the other, after which the slag and the metal can be removed by a 90 hoist and deposited at some suitable place. The parts of the crucible are then reassembled and moved to a point where it may be relined, and the operation repeated.

It will be seen from the foregoing that 95 the crucible is simple and economical in construction, and lasting in character, and that it is adapted for a variety of uses. By virtue of its separable character, it facilitates the handling of the contents, and it is so 100 simple that a novice can assemble or separate the parts.

I claim:—

A crucible for use in metal founding operations and the like composed of separable members, and a continuous, refractory, friable lining therefor permitting of the ready separation of the members to expose the contents.

In testimony whereof I have hereunto signed my name in the presence of the two subscribed witnesses.

JOHN J. BOERICKE.
